UNITED STATES PATENT OFFICE.

LOUIS REVIS, OF BLUE BOUND, ILLINOIS.

BURIAL-VAULT MOLD.

Application filed January 23, 1923. Serial No. 614,443.

To all whom it may concern:

Be it known that I, LOUIS REVIS, a citizen of the United States, residing at Blue Mound, in the county of Macon and State of Illinois, have invented certain new and useful Improvements in Burial-Vault Molds, of which the following is a specification.

This invention relates to molds for concrete and other plastic burial vaults and has as one of its primary objects to provide a mold by the use of which the vault body and lid may be conveniently, economically, and expeditiously produced.

Another object of the invention is to so construct the mold that its parts will not be liable to become disarranged during the molding operation.

Another object of the invention is to so construct the mold that the component parts thereof may be readily disassembled when the body or lid, as the case may be, is to be removed therefrom.

In the accompanying drawings:

Figure 1 is a top plan view of the mold provided for producing the vault body;

Figure 2 is a view partly in elevation and partly in section on the line 2—2 of Figure 1;

Figure 3 is a vertical transverse sectional view on the line 3—3 of Figure 2;

Figure 4 is a view similar to Figure 2 illustrating the mold for the lid of the vault;

Figure 5 is a vertical transverse sectional view on the line 5—5 of Figure 4;

Figure 6 is a vertical transverse sectional view through a vault produced by the use of the mold.

Referring to Figs. 1 to 3, inclusive, which illustrate the mold structure employed in producing the body of the vault, the numeral 1 indicates a base, which may be of wood or any other suitable material and preferably of rectangular form. In order to retain in place upon the base the outer and inner sections of the mold constituting respectively the mold chamber and the core, cleats 2 and 3, preferably of angle iron, are secured upon the upper surface of the base 1 and extend respectively parallel to the longitudinal and end edges of said base, and other cleats 4 and 5 are secured upon

the upper face of said base and respectively extend in spaced parallel relation to respective ones of the cleats 2 and 3. 55

The outer section of the mold, or in other words, the mold chamber proper, is indicated in general by the numeral 6 and the same comprises side walls 7 and end walls 8. The walls 7 and 8 are preferably each formed from an integral sheet of metal and the walls are respectively reinforced by angle irons 9 and 10 riveted or otherwise secured upon their outer faces and extending longitudinally thereof, these angle irons preventing buckling or other distortion of the said walls and permitting the walls to be made of relatively thin sheet metal. The walls are assembled with their ends meeting 70 and they are separably connected at their meeting ends or, in other words, at the corners of the said outer section or mold chamber by providing them at their ends with obliquely outwardly directed flanges 11 75 through which bolts or other fastening elements 12 are engaged or secured. Owing to the formation of these flanges and the fact that they are firmly secured together face to face, leakage of the plastic material being 80 molded is effectually prevented. The lower portions of the plates comprising the walls 7 and 8 are deflected outwardly as at 13 and thence extended downwardly as at 14 so that

the vault body, as shown in Figure 6 of the drawings and indicated by the reference letter B will be provided upon its outer side around its open top with a thickened shoulder portion C. By reference to the drawings it will be observed that the outer section or mold chamber is disposed in position resting upon the upper side of the base 1 and that the lower edges of the portions 14 of its walls 7 and 8 seat beside the inner sides of the cleats 2 and 3, the said section 6 being in this manner restrained against displacement either longitudinally or horizontally. 95

The inner section of the mold, or in other words, the core, is indicated in general by the numeral 15 and the same comprises side walls 16, end walls 17, and corner wall sections 18. Each of the side walls 16 is preferably formed from a single integral sheet of metal which is preferably reinforced by upper and lower angle irons 19 riveted 105

otherwise secured to the inner face thereof and extending longitudinally thereof, these angle irons terminating slightly short of the vertical end edges of the said side wall sections whereby each section has end marginal portions 20 to the inner faces of which are secured vertical angle irons 21. The end wall sections 17 are likewise each in the form of an integral plate of sheet metal reinforced by angle irons 22 secured to the inner face thereof, vertical angle irons 23 being secured to the end marginal portions of the said end wall sections and corresponding to the angle irons 21. Each corner section 18 comprises relatively right angularly disposed side and end wings 24 and 25, these corner sections being likewise formed of sheet metal and having their wings 24 and 25 reinforced by angle irons 26 and 27. The angle irons 26 and 27 terminate short of the outer vertical edges of the respective wings so that relatively broad marginal portions 28 are provided and to these portions, inwardly of the edges thereof, are secured vertically disposed angle irons 29. Bolts or other fastening elements 30 are secured through the meeting angle irons 21 and 29 and 23 and 29 and in this manner the side, end, and corner sections of the core are separably connected together, it being observed by reference to Figure 1, that the projecting marginal portions 28 of the corner sections will overlap the attached wings of the angle irons 21 and 23 of the side and end sections so that the juncture of the edges of the sections will break joint with the juncture of the angle irons to prevent leakage of the plastic material. The core is adapted to be disposed upon the base 1 of the mold with the lower edges of its side and end walls seating against the outer sides of the cleats 4 and 5 as will be evident by reference to Figures 2 and 3 of the drawings.

In order that the body B of the vault may be provided at its open top with a seating shoulder S and with a sealing groove G, each section comprising the core is provided upon its outer side and along its lower marginal portion with a longitudinally extending bead 31 provided upon its outer side with an outstanding rib 32, as best shown in Figures 2 and 3 of the drawings. The side walls 16 of the core are relatively braced so as to prevent distortion, by means of transverse brace rods 33 which have downturned end portions 34 removably seated in openings 35 formed in the horizontal wings of the upper angle irons 19.

The top of the core is indicated in general by the numeral 36 and comprises a rectangular sheet metal plate 37 which is disposed to rest at its marginal portions upon the upper edges of the side, end, and corner sections of the core and closes the top of the said core. The plate 37 is braced at its inter-

mediate portion, against sagging, by a T-iron 38 which is seated at its ends in sockets 39 formed in supporting plates 40 secured to the inner faces of the slide wall sections 16 of the core near the upper edges thereof, the T-iron extending transversely beneath and being secured to the under side of the said plate 37 at a point substantially midway between its ends. The engagement of the ends of the T-iron in the sockets in the supporting plates 40 serves not only to prevent downward displacement or distortion of the intermediate portion of the plate 37, but also serves as a means for properly centering this plate upon the top of the core and preventing its accidental displacement during the molding operation.

From the foregoing it will be understood that after the two parts of the mold have been set up as shown in Figures 1, 2 and 3, the plastic material may be poured into the mold, filling the spaces between the side and end walls of the mold chamber and core and also filling the space within the mold chamber above the top plate 36 of the core, the surface of the plastic material being troweled off flush with the upper edges of the walls of the mold chamber and the whole being then allowed to set. After it has set, the mold with the vault body therein may be overturned, the base 1 removed, the securing elements 30 removed from engagement through the angle irons, and the sections comprising the core separated and removed from within the vault body. When the side walls of the core are removed, the socket plates 40 are, of course, lifted from the ends of the T-iron 38 which is secured to and extends transversely of the top plate 37. The said iron then serves as a handle or member which may be gripped by a tool so as to permit the top plate to be lifted from the formed vault body.

The mold illustrated in Figs. 4 and 5 of the drawings and employed in producing the lid of the vault comprises a base 41 upon the upper face of which is arranged and suitably secured a core 42 which is, generally speaking, of a transversely arched contour, the arched upper surface, which is indicated by the numeral 43, terminating in preferably flat downwardly and outwardly inclined surfaces 44 at the sides and ends of the core. The core 42 is surrounded by a rectangular mold frame indicated in general by the numeral 45 and comprising sides 46 and ends 47. The sides and ends of the mold frame are separate from one another, and each member of the frame is provided upon its outer side with a plurality of attaching brackets 48, each having an outstanding lower end portion 49 occupying a plane with the lower edge of the respective frame member and adapted to rest upon the upper surface of the base 1 when the frame

members are assembled upon the said base. Studs 50 are anchored in the base at suitably located points, and wing nuts 51 are removably threaded onto the studs and bear against the upper sides of the outstanding portions 49 of the bracket members 48, the studs projecting, of course, through openings in the said portions 49. The frame members are provided upon their inner sides 10 with ribs 52 which correspond in general shape and function to the ribs 32 previously described and which serve to form about the lid of the vault a sealing groove, indicated by the reference letter G in Figure 6. By 15 reference to Figures 4 and 5 it will be observed that the members of the mold frame are inclined upwardly and inwardly so that the lower portion of the lid of the vault has a downwardly and outwardly inclined outer 20 surface at its sides and ends thus providing, between the lid and the open top of the body, a continuous pocket P to receive any suitable sealing material which may be poured into the said pocket, the material, of 25 course, entering the grooves G and G'.

In producing the lid, the mold frame is secured upon the base 41 and the plastic material of which the lid is to be formed is applied over the core and into the space between the lower portion of the core and the mold frame, being troweled to a smooth surface and permitted to set. After the material has set, the wing nuts 51 may be removed and the mold frame members then

separated from the base so as to permit of 35 bodily removal of the molded lid.

Having thus described the invention, what is claimed as new is:

1. In a mold of the class described, a base, a core upon the base provided at its bottom 40 portion and at its exterior with a form element outstanding from the plane of its walls and a rib extending longitudinally of said form element between the upper and lower edges of the same, and mold walls 45 upon the base surrounding the core and having their lower portions outwardly deflected, the said walls being separable from each other and from the base.

2. In a mold of the class described, a base, 50 a mold chamber upon the base, and a core upon the base within the mold chamber, the said core comprising a rectangular hollow body, a top plate closing the upper end of the core body and occupying a plane below 55 the plane of the top of the mold chamber, and means supported by the opposite sides of the core and sustaining the intermediate portion of the said top plate, the said means comprising a transverse angle bar 60 secured between its ends to and in contact throughout its entire length with the under side of the top plate, and socket members upon the said sides of the core receiving 65 the ends of said bar.

In testimony whereof I affix my signature.

LOUIS REVIS. [L. S.]
